TYPEWRITING MACHINE

George G. Going, Glenbrook, Conn., assignor to
Remington Typewriter Company, Ilion, N. Y.,
a corporation of New York

Application October 15, 1931. Serial No. 568,971

23 Claims. (Cl. 197—161)

My invention relates to typewriting and like machines and more particularly to ribbon feed and automatically operating reversing mechanism therefor.

5 The main object of my invention, generally stated, is to provide a very simple and inexpensive, yet highly efficient mechanism of the character referred to.

To the above and other ends which will herein-
10 after appear, my invention consists in the features of construction, arrangements of parts and combinations of devices hereinafter described and particularly pointed out in the appended claims.

In the accompanying drawings, wherein like
15 reference characters indicate corresponding parts in the different views—

Fig. 1 is a fragmentary, enlarged, detail, vertical sectional view of the construction, the section being taken on the line 1—1 of Fig. 2 and looking in the direction of the arrows at said line.

Fig. 2 is an enlarged, detail, fragmentary top plan view of the same.

Fig. 3 is an enlarged, detail, perspective view of
20 one of the ribbon controlled carriers and a portion of one of the interponents or reversing rods carried thereby.

Fig. 4 is an enlarged detail, fragmentary, sec-
25 tional view of the same, the section being taken on the line 4—4 of Fig. 2 and looking in the direction of the arrows at said line.

Fig. 5 is an enlarged, detail, fragmentary, sec-
30 tional view of a portion of the ribbon feed mecha-
nism, the section being taken on the line 5—5 of
35 Fig. 1 and looking in the direction of the arrows at said line.

Fig. 6 is an enlarged, detail, sectional view
40 taken through one of the driving gears and show-
ing the parts as they appear before said gear is
fixed on its driving shaft.

Fig. 7 is an enlarged, detail, end view of the
45 same gear after it is fixed on its shaft, the latter
being shown in section on the line of its engaging
notch.

Fig. 8 is an enlarged, detail sectional view
50 taken on the line 8—8 of Fig. 7 and showing the
parts as they appear when the gear is fixed to the
shaft.

Fig. 9 is an enlarged, detail face view of the
55 endless detent spring.

My invention is shown, in the present instance,
embodied in a typewriting machine such as is
disclosed in my copending application Ser. No.
538,429, filed May 19, 1931. It should be under-
stood, however, that the invention is not re-

stricted to use in such machine, but may be em-
bodied in typewriting and like machines generally,
wherever found available.

It is one of the objects of the present invention
to provide a simple yet highly efficient ribbon feed
and automatically operating reversing mecha-
nism for typewriting and like machines of such
character that nearly all of the parts thereof
may be made from sheet metal and the mecha-
nism may be constructed and assembled at an
extremely low cost.

With these ends in view I mount the main hori-
zontally disposed driving shaft 1 of the ribbon
feed mechanism in bearing openings in the sheet
metal side plates 2 of the frame of the machine.
This shaft extends transversely of the machine
and is free to turn and to be moved longitudinally
in said bearing openings and projects at its ends
beyond said side plates 2 to provide finger pieces 1^a
by which the shaft may be turned to hand feed
the ribbon or may be employed to shift the shaft 1
longitudinally, when desired, to reverse the direc-
tion of feed of the ribbon by hand.

A main driving ratchet wheel 3 is, or may be,
firmly fastened to the shaft 1 in the same man-
ner that the ribbon spool driving gears are fast-
tened to the shaft, as will be hereinafter ex-
plained.

Two oppositely disposed crown driving gears
4 and 5 are fixed on the shaft 1 for transmitting
feed movement to one or the other of the ribbon
spools. Preferably each of these crown gears is
struck up from a single piece of sheet metal.

Coacting with the ratchet wheel 3 is a feed
pawl 6 of sheet metal and having parallel ears
7 by which it is pivoted at 8 to an upwardly
extending arm 9 on a sheet metal universal bar
10. Said universal is pivoted at 11 on arms 12
of a supporting frame or casting 13. From an
inspection of Fig. 1, it will be seen that a projec-
tion 14 near the heel of each type bar 15, piv-
oted at 16 on the segment which forms part of
the casting 13, coacts with and actuates the uni-
versal bar as a type bar approaches the platen
17. The universal bar thus actuated vibrates
the feed pawl 6 to turn the ratchet wheel 3, and
the shaft 1 and driving wheels 4 and 5 a corre-
sponding distance. A sheet metal holding pawl
18 is pivoted on the pivot screws 11 and coacts
with the ratchet wheel 3 to hold it against back-
ward movement during the return movement of
the feed pawl 6 to normal position after having
advanced the ratchet wheel 3. A single con-
tractile spring 19, is connected at one end to the
feed pawl 6 and at its other end to the holding
pawl 18.

100

110

100
105
110

100
105
110

pawl 18; holding both of said pawls in engagement with the ratchet wheel 3. From an inspection of Fig. 2 it will be seen that both the feeding pawl 6 and holding pawl 18 are of sufficient width to coat with the ratchet wheel 3 in either of the positions to which it may be shifted with the shaft 1 in the longitudinal shifting movement of the latter.

Each of the crown gears 4 and 5 is adapted to 10 coat with spur teeth on a driven gear 20 carried by and riveted to the lower end of an upright shaft 21 by which the companion ribbon spool 22 is driven. Each shaft 21 extends at right angles to the main driving shaft 1, and 15 is received at its lower end portion in a bearing 13^a in the casting 13, whereas, the upper end portion of the shaft is received in a bearing opening in an inturned bracket arm 23 formed on a side plate 2 of the frame.

20 In the present instance each ribbon spool 22 is detachably connected to its driving shaft 21 to turn therewith by the following means:

A centrally pierced connecting washer 24 for each spool is provided with oppositely disposed 25 notches 25 in the edges thereof. In these notches is received depending lugs 26 struck from the lower flange of the associated ribbon spool to connect each washer and its spool to turn together but permit the latter to be lifted up off 30 and disconnected from the washer when desired. The upper end of each shaft passes freely through a bearing opening in an angular ribbon guide 27 slotted at 28 in its upright arm to receive and guide the ribbon *a* as it 35 passes from one spool to the other. Each washer 24 bears against the upper end of the companion shaft 21 and is clamped thereto by a shoulder 29 of a screw 30. The shoulder 29 is formed at the point where the elongated head of the screw 40 joins a reduced shank 31 threaded at its lower end portion where it is received in a tapped opening in the upper end portion of the companion spool shaft 21. The stem 31 of the screw passes through the central opening in the companion washer 24, whereas the elongated head of the screw provides a support which receives the hub 32 of the companion spool and holds it 45 centered on the associated washer 24 that is clamped to the shaft by said screw. It will be 50 understood that each shaft 21 with its screw 30 is supported in place by the associated washer 24 bearing against the companion ribbon guide 27 which in turn is supported by the companion bracket arm 23. On the other hand the spur gear 20 at the lower end of each shaft 21 bears 55 upward against the companion bearing 13^a of the casting 13 and prevents an upward displacement of the shaft.

It also will be understood, of course, that the 60 longitudinal position of the shaft 1 determines which spool 22 shall be driven through the co-operation of its driving gear 4 or 5 with the associated driven gear 20 to wind the ribbon on said driven spool, and that when one of said driving gears 4 or 5 is thrown into mesh with its companion driven gear 20, the other driving gear will be thrown out of mesh with its companion driven gear.

I have provided in the present instance very 65 simple automatically operating means for shifting the shaft 1 longitudinally as indicated above when the ribbon is about exhausted from one spool, thus automatically changing the direction of feed of the ribbon.

70 Such means will now be described.

A sheet metal ribbon controlled carrier, controlling member or lever which is shown in detail in Fig. 3, is associated with each ribbon spool. In each instance this device is indicated as a whole by the reference numeral 33 and 80 comprises an arm, follower or contact member 34 that is adapted to pass between the flanges of the associated ribbon spool and bear against the outer surface of the ribbon wound thereon only after the ribbon is almost completely wound thereon, as indicated at the right-hand side of Fig. 2. Each controlling member 33 is provided with pivots or lugs 35 projecting from the top and bottom edges thereof and intermediate its ends. The lower lug 35 is received in a pivot opening 36 in the companion bracket arm 23, whereas, the upper pivot lug is received in a pivot opening 37 in a top plate member 38 (see Fig. 4) detachably secured to the side plates 2 of the frame.

Intermediate its ends each member 33 is provided with an integral leaf spring 39 struck up from the body portion of said member and adapted to bear against the inner face of the adjacent side plate 2 of the frame, as shown in Fig. 2. The force of this spring tends to maintain its associated member 33 in the position shown at the left-hand side of Fig. 2, and with the arm 34 thereof out of contact with the ribbon on the associated spool until the ribbon is nearly fully wound thereon. When the ribbon is nearly fully wound on a spool such wound ribbon will engage the arm 34 of the associated controlling member 33 and shift it a small distance from the position shown at the left-hand side of Fig. 2 to a position corresponding to that indicated at the right-hand side of said figure.

A second arm 40 on each carrier 33 extends therefrom on the opposite side of the companion shaft 21 and has a terminal portion 40^a bent at an angle to the body portion of said arm 40; at right angles thereto in the present instance. A key-hole slot is formed in the arm 40—40^a across the angle thereof; the enlarged portion 41 of said slot being in the bent down terminal portion 40^a, whereas the contracted portion 42 of the slot is in the horizontal body portion of the arm 40.

A reversing or controlling member or rod 43 is provided with a circumferential groove 44 therein. This member is in the nature of a wedging member or floating interponent preferably serrated longitudinally at 45 to provide an effective surface for the engagement of the teeth of the companion driving and driven gears therewith, as will presently appear. Each of these rods 43 is loosely suspended by a swivel connection from its upper end on the companion carrier 33 and is free to swing at its lower end in any direction. In order to detachably connect each rod 43 to its companion carrier 33, it is merely necessary to first turn the rod to a position other than that which it assumes when in use in the machine; to substantially a horizontal position in the present instance. Then insert the grooved end of the rod through the enlarged opening 42 until the groove 44 in the rod registers with the contracted portion 42 of the opening. Then turn the rod down to its position of use so that the rod will assume a position such as that shown in Fig. 3 with walls of the narrow part 42 of the slot received in the groove 44, thus suspending the rod at its upper end on the carrier for free swinging movement at its lower end.

150

When the parts are thus disposed the rod will hang down either into the bight between the associated driving and driven gears, and in contactive engagement with the teeth thereof as shown at the right-hand side of Fig. 2, or out of contactive engagement with said gears, as shown at the left-hand side of said figure. Whether the reversing rod 43 is in one or the other of these positions depends on the position 5 of the associated controlling member 33 which carries it. The tendency of the spring 39 of each controlling member 33 is to hold the associated reversing rod out of cooperating relation with its companion gears. When, however, a spool 10 is nearly filled, as shown at the right-hand side of Fig. 2, the ribbon being wound on such spool will gradually shift the companion controlling member 33 from the position indicated at the left-hand side of Fig. 2 to that indicated at the 15 right-hand side thereof thus shifting the companion rod 43 into contactive engagement with the companion driving and driven gears. It will be understood from an inspection of Fig. 5 that each interponent or reversing rod 43, when 20 moved to effective position, will first be carried by its carrier 33 into the bight between the two companion gears and will rest lightly by its own weight against the teeth thereof. The serrations in the rod thus engaged by the teeth of the 25 gears aid in causing the gears to carry the lower end of the rod along with and between them, as indicated in Fig. 5; the rod progressing successively from the uppermost dotted line position to the full line position as the parts are shown 30 in said figure. The reversing rod in being thus moved along with and between the gears acts as a wedge and by its wedging action separates the intermeshed gears, shifting the shaft 1 longitudinally to the left, as the parts are shown in 35 Fig. 5. This results in throwing the driving gear 4 for the other ribbon spool into mesh with its companion driven gear 20, and in turning the left-hand spool clockwise and reversing the direction of feed of the ribbon. The ribbon then 40 continues to be wound on the left-hand spool until it is almost fully wound thereon when the left-hand gears will be automatically separated as described above, thus again driving the right-hand spool through its gearing and again winding the ribbon on the right-hand spool. 45

It will be understood that even though a reversing rod 43 remains in the bight between the companion gears of a fully wound spool until ribbon has been wound off said spool sufficiently to enable the companion carrier to move said rod to 50 left-hand Fig. 2 position, no harm can result because the associated gears are out of mesh and the gear 20 thereof is moving in the reverse direction at this time and tending to move the companion reversing rod out of the bight between said gears and not into the bight as is the case when the associated gears are in mesh.

By holding the contacts or arm 34 out of contact with the ribbon at all times except when the 55 ribbon is almost fully wound on one of the spools and the direction of the feed of the ribbon is about to be reversed, there is no retardation to the feed of the ribbon by said arms except at such short intervals. Nevertheless, the arms 34 prevent at 60 all times the coils of the ribbon from dropping off or being displaced from between the flanges of the spools.

In order to insure a complete longitudinal shifting movement of the shaft 1 at each reversing 65 operation, and prevent the shaft from being

accidentally displaced from its shifted position, I provide a novel spring detent mechanism which is very simple in construction and cheap to manufacture and assemble. This mechanism will now be described.

Referring more particularly to Fig. 5 it will be seen that the right-hand end portion of the shaft 1 not only extends through a bearing opening in a side plate 2 of the frame, but also extends loosely through slots 46 in two adjacent arms 47 of the casting 13. The arms 47 are separated to provide an intervening space 48. The right-hand end portion of the shaft 1 has two circumferential grooves 49 therein separated by an intermediate cam 50, having oppositely disposed inclined faces. An endless coiled contractile spring 51, shown in detail in Fig. 19, surrounds the shaft 1 and is seated in one or the other of the grooves 49 therein, depending on the longitudinal position of the shaft 1. As the shaft 1 is shifted longitudinally the spring will coat with the inner face of one or the other of the arms 47, depending on the direction of shifting movement of the shaft, and hold the spring while the shaft is shifted independently thereof, say, to the 100 right in Fig. 5. When the high intermediate portion of the cam 50 passes the spring the contractile force of the latter operating on an inclined face of the cam will complete the longitudinal shifting movement of the shaft, bringing, in the circumstances supposed above, the driving gear 5 into full meshing engagement with its companion gear 20, as shown at the right-hand side of Fig. 2. This results in holding the shaft 1 against accidental displacement from said shifted position. The parts will operate in a like manner when the shaft 1 is shifted to the left from the Fig. 2 position, except that the detent spring will complete the movement of the shaft 1 to the left instead of to the right.

As a further aid to the production of an inexpensive construction I prefer to fixedly connect each of the gears 4 and 5 and the ratchet wheel 3 to the shaft 1 by the following means and in the manner to be now described.

Referring more particularly to Figs. 6, 7 and 8 it will be seen that the shaft 1 is provided with notches 52 on opposite sides thereof where either of the gears 4 and 5 or the ratchet wheel 3 is to be secured to the shaft. The bottom wall 53 of each notch is flat, as shown in Fig. 7, to form an engagement with the companion gear, as will presently appear. The width of each notch 52 corresponds substantially to the thickness of the stock from which the gears 4 and 5 and the ratchet wheel 3 are made. Each of said gears and the ratchet wheel is first formed with a cup-like formation at the center of the body portion thereof, as indicated at 54 in Fig. 6. The central portion of each gear and the ratchet wheel is pierced with an opening that conforms in shape to the cross section of the shaft 1 where the notches 52 are provided therein. Each of the gears and the wheel are then moved along the shaft until the walls of the pierced portion thereof register with the companion notch 52. The cupped portion 54 is then flattened to bring it in the same plane as the remainder of the body portion of the wheel or gear, thus forcing the metal into the companion grooves 52, as shown in Figs. 7 and 8, and firmly connecting the gears and wheel to the shaft without the use of any hubs, screws etc. and without incurring the expense involved in the employment thereof.

pawl 6 by which a feed of the ribbon is effected at each printing operation is returned to normal position by a suitable spring, a coiled expansion spring 55, shown in part in dotted lines in Fig. 1, 5 being employed for this purpose in the present instance.

The universal bar structure, as shown in the present construction, constitutes a carrier for the feed dogs 56 and 57 which coact with a feed rack 10 58 carried by the carriage. This structure is not claimed herein but will be made the subject matter of a separate divisional application.

From the foregoing description it will be seen that I am enabled by my present invention, to 15 provide a very simple and yet highly efficient construction, the parts of which are inexpensive to manufacture and assemble, thus contributing materially to the production of a typewriting machine which may be manufactured at a very small 20 cost.

Various changes may be made in the construction, and parts thereof may be omitted without departing from my invention, as it is defined in the accompanying claims.

25 What I claim as new and desire to secure by Letters Patent is:

1. The combination of ribbon spools, means for turning said ribbon spools comprising a longitudinally shiftable driving shaft, driving gears carried thereby, companion driven gears meshing with one or the other of said driving gears depending on the longitudinal position of said driving shaft thus determining the direction of the feed of the ribbon, and ribbon reversing means 30 controlled by the ribbon and comprising loosely supported reversing members, each mounted to be moved into and out of cooperation with the teeth of companion intermeshing gears and be carried along therewith between such intermeshing gears 35 to separate them and thus effect a longitudinal shift of said shaft to reverse the direction of feed of the ribbon.

2. The combination of ribbon spools, means for turning said ribbon spools comprising a longitudinally shiftable driving shaft, driving gears carried thereby, companion driven gears meshing with one or the other of said driving gears depending on the longitudinal position of said driving shaft thus determining the direction of the feed 45 of the ribbon, a movably supported controlling member associated with each ribbon spool and controlled in its movement by the ribbon, and a pendent reversing member loosely supported by each controlling member and moved thereby into 50 and out of effective position and when in the effective position disposed to be drawn between companion driving and driven gears by the action of such gears thereon and thus shift said shaft longitudinally to reverse the direction of the feed 55 of the ribbon.

3. The combination of ribbon spools, means for turning said ribbon spools comprising a longitudinally shiftable driving shaft, driving gears carried thereby, companion driven gears meshing 65 with one or the other of said driving gears depending on the longitudinal position of said driving shaft thus determining the direction of the feed of the ribbon, and means for shifting said shaft longitudinally comprising two reversing 70 rods one for each spool, each of said rods being swivelled at its upper end to a movable support to swing into position between and to be engaged by and carried along with the teeth of the associated driving and driven gears, and ribbon 75 controlled means associated with each of said

movable supports to control its movement and thus move the companion rod into and out of the range of the teeth of the associated driving and driven gears.

4. Means for feeding and for reversing the direction of the feed of a ribbon, comprising intermeshing gears, wedging means for entering between and wedging said gears apart by the action of the gears thereon, and ribbon controlled means for bringing said wedging means into cooperative relation with said gears.

5. Means for feeding and for reversing the direction of the feed of the ribbon, comprising two shafts arranged at right angles to each other, a crown gear carried by one of said shafts, an intermeshing spur gear carried by the other of said shafts, a wedging member that is engaged by the teeth of said gears and carried thereby between the gears to separate them from meshing engagement, and means controlled by the ribbon for bringing said wedging member into position where it will cooperate with the teeth of said gear wheels.

6. Means for feeding and for reversing the direction of the feed of the ribbon, comprising a pair of intermeshing gears, a ribbon controlled lever, and an interponent carried by said lever and depending therefrom and loosely supported thereby, the construction and relation of the parts being such that when said lever is in one position said interponent will be supported to be engaged by and carried along with and between the teeth of said gear wheels and thus effect a separation and disengagement thereof one from the other to bring about a reverse in the direction of the feed and when said lever is in another position said interponent will be held out of contact with the teeth of said gear wheels.

7. The combination of a pair of ribbon spools, a driven gear connected to each spool, a companion driving gear adapted to mesh with each driven gear, a longitudinally shiftable driving shaft on which said driving gears are mounted, the relation of the parts being such that when the companion gears for one spool are in mesh those for the other spool are out of mesh, a ribbon controlled lever for each spool, and an interponent carried by each of said levers and depending therefrom and loosely supported thereby, the construction and the relation of the parts being such that when each lever is in one position its companion interponent will be supported to be engaged by and carried along with and between the teeth of the companion gears and thus effect a separation thereof and a longitudinal shifting of said driving shaft to bring about a reverse in the direction of the feed of the ribbon and when each lever is in another position the associated interponent will be held out of contact with the teeth of the companion gears.

8. The combination of a pair of ribbon spools, and ribbon feed and automatically operating reversing means for said spools comprising a sheet metal controlling device associated with each ribbon spool, each controlling device being pivoted intermediate its ends and having one arm that constitutes a contact which bears against the ribbon on the associated ribbon spool and also having an integral leaf spring that bears against a fixed part of the machine and causes said arm to bear against the ribbon and also tends to hold its controlling device in its normal position out of contact with the ribbon, and a reversing member carried by the other arm of each of said sheet metal controlling devices.

9. The combination of a pair of ribbon spools,

- and ribbon feed and automatically operating reversing means for said spools comprising a sheet metal controlling device associated with each ribbon spool, each controlling device being pivoted intermediate its ends and having one arm that constitutes a contact which bears against the ribbon on the associated ribbon spool and also having a spring that causes said arm to bear against the ribbon, and a reversing member carried by the other arm of each of said sheet metal controlling devices, each reversing member being in the nature of a depending rod loosely supported on the companion controlling device, and shiftable ribbon feed devices with which each reversing device coacts. 10 15 20 25 30 35 40 45 50 55 60 65 70 75 80 85 90 95 100 105 110 115 120 125 130 135 140 145 150
10. The combination of a pair of ribbon spools, and ribbon feed and automatically operating reversing means for said spools comprising a sheet metal controlling device associated with each ribbon spool, each controlling device being pivoted intermediate its ends and having one arm that constitutes a contact which bears against the ribbon on the associated ribbon spool and also having a spring that causes said arm to bear against the ribbon, a reversing member carried by the other arm of each of said sheet metal controlling devices, each reversing member being in the nature of a depending rod loosely and detachably supported on the companion controlling device for universal movement thereon, and relatively shiftable ribbon feed gears with which each reversing device coacts and which are separated by the direct coaction of the companion depending rod with the teeth thereof. 20 25 30 35 40 45 50 55 60 65 70 75 80 85 90 95 100 105 110 115 120 125 130 135 140 145 150
11. The combination of a shaft mounted for turning and for longitudinal shifting movement, means for effecting a turning movement of said shaft at each printing operation, driving gears carried by said shaft, driven gears with which said driving gears are adapted to mesh, ribbon spools driven by said driven gears, the construction and arrangement of the parts being such that one pair of associated driven and driving gears are out of mesh when the other associated pair of such gears are in mesh depending on the longitudinal disposition of said shaft, and ribbon controlled means for shifting said shaft longitudinally comprising a ribbon controlled member associated with each ribbon spool and adapted when the ribbon is about fully wound on its spool to move into position between the companion driven and driving gears and to be carried by the teeth thereof between such gears to separate them and shift said shaft longitudinally. 25 30 35 40 45 50 55 60 65 70 75 80 85 90 95 100 105 110 115 120 125 130 135 140 145 150
12. The combination of a universal bar, a ribbon feed pawl actuated thereby, a ratchet wheel driven by said pawl, a shaft mounted for turning and for longitudinal movement and on which said ratchet wheel is mounted, driving gears carried by said shaft, driven gears with which said driving gears are adapted to mesh, ribbon spools driven by said driven gears, the construction and arrangement of the parts being such that one pair of associated driven and driving gears are out of mesh when the other associated pair of such gears are in mesh depending on the longitudinal disposition of said shaft, and ribbon controlled means for shifting said shaft longitudinally comprising a ribbon controlled member associated with each ribbon spool and adapted when the ribbon is about fully wound on its spool to move into position between the companion driven and driving gears and to be carried by the teeth thereof between such gears to separate them and shift said shaft longitudinally. 25 30 35 40 45 50 55 60 65 70 75 80 85 90 95 100 105 110 115 120 125 130 135 140 145 150
13. The combination of a type-bar-actuated universal bar, a ribbon feed pawl carried and actuated thereby, a ribbon feed ratchet wheel with which said pawl coacts, a shaft mounted for turning and for longitudinal movement and on which said ratchet wheel is fixedly mounted, said ribbon feed pawl being of sufficient width to coact with said ratchet wheel irrespective of the position to which said shaft may be shifted longitudinally, driving gears carried by said shaft, driven gears with which said driving gears are adapted to mesh, ribbon spools driven by said driven gears, the construction and arrangement of the parts being such that one pair of associated driven and driving gears are out of mesh when the other associated pair of such gears are in mesh depending on the longitudinal disposition of said shaft, and ribbon controlled means for shifting said shaft longitudinally comprising a ribbon controlled member associated with each ribbon spool and adapted when the ribbon is about fully wound on its spool to move into position between the companion driven and driving gears and to be carried by the teeth thereof between such gears to separate them and shift said shaft longitudinally. 25 30 35 40 45 50 55 60 65 70 75 80 85 90 95 100 105 110 115 120 125 130 135 140 145 150
14. The combination of a pair of ribbon spools, ribbon feeding means comprising a pair of gears for each spool mounted for relative movement into and out of mesh, and reversing means for effecting such relative movements of said gears comprising a floating interponent associated with each of said spools and supported only at its upper end and free to swing at its lower end in any direction and drop into the bight between its companion gears and be engaged by the teeth thereof and carried along therewith to effect a separation of such associated gears, and a movable ribbon controlled controlling member for each spool and which constitutes a support for the associated interponent and by which it is moved into and out of position where it may be engaged by its associated gears. 25 30 35 40 45 50 55 60 65 70 75 80 85 90 95 100 105 110 115 120 125 130 135 140 145 150
15. The combination of a pair of ribbon spools, ribbon feeding means comprising a pair of gears for each spool mounted for relative movement into and out of mesh, and reversing means for effecting such relative movements of said gears comprising a floating interponent associated with each of said spools and supported only at its upper end and free to swing at its lower end in any direction and drop into the bight between its companion gears and be engaged by the teeth thereof and carried along therewith to effect a separation of such associated gears, a movable ribbon controlled controlling member for each spool and which constitutes a support for the associated interponent and by which it is moved into and out of position where it may be engaged by its associated gears, and means which enables each of said interponents to be readily attached to or detached from the companion controlling member by moving the interponent to a position at an angle to any position it can assume in the operation of the machine. 25 30 35 40 45 50 55 60 65 70 75 80 85 90 95 100 105 110 115 120 125 130 135 140 145 150
16. Ribbon feeding and reversing means comprising gears relatively shiftable out of mesh, and means for thus shifting said gears comprising a movable ribbon controlled carrier, an interponent carried and movable thereby into and out of cooperative relation with said gears, said interponent being serrated for engagement with the teeth of the gears, and means for readily connecting and disconnecting said interponent and carrier. 25 30 35 40 45 50 55 60 65 70 75 80 85 90 95 100 105 110 115 120 125 130 135 140 145 150

17. Ribbon feeding and reversing means comprising two relatively movable members supported one by the other, and means for readily connecting and disconnecting said members comprising a bent portion of one member having a key-hole slot extending across the bent portion thereof and a headed portion with a reduced neck on the other member that may be received in and withdrawn from said key-hole slot only when the two members are relatively disposed in a position they do not assume when in use in the machine.
18. The combination of a ribbon spool, a screw with a shoulder and an elongated head on which said spool is received and by which it is centered, a driving shaft with which said screw has a threaded connection, a washer intermediate an end of said shaft and the shoulder on said screw and by which the washer is firmly clamped to turn with the shaft, and an interlocking connection between the spool and said washer to cause the two to turn together without interfering with the removal of the spool.
19. In a ribbon feed mechanism the combination of a shaft having a notch therein with a flat bottom wall, and a sheet metal member having an opening that conforms to the cross section of the shaft at the notched portion thereof and which member is flattened from a cup form to secure the member to the shaft at the notched portion thereof.
20. Ribbon reversing mechanism comprising a sheet metal ribbon-controlled controlling-member having one portion thereof bent at an angle to another portion and having a key hole slot across the bend thereof with the enlarged portion of the slot to one side of the bend and the contracted portion of the slot at the other side of the bend, and a headed reversing device detachably connected with said controlling member, the head of the reversing device passing through the enlarged portion of the key hole slot in assembling the parts and sustained in position in the contracted portion of the slot.
21. Ribbon reversing mechanism comprising a sheet metal ribbon-controlled controlling-member having one portion thereof bent at an angle to another portion and having a key hole slot across the bend thereof with the enlarged portion of the slot to one side of the bend and the contracted portion of the slot at the other side of the bend, and a headed reversing device detachably connected with said controlling member, the head of the reversing device passing through the enlarged portion of the key hole slot in assembling the parts and sustained in position in the contracted portion of the slot.
22. The combination of a ribbon spool, a movably mounted ribbon-controlled controlling-member having an arm that bears against and is controlled by the ribbon on the spool when such spool closely approaches a fully wound condition and is then shifted by the ribbon before the latter is fully wound on the spool, ribbon reversing means controlled by said controlling-member, and spring means which bears against a fixed part of the machine and tends to hold said controlling member in its normal position out of contact with the ribbon until the spool closely approaches such fully wound condition and to return the controlling member to such normal position as the ribbon is unwound from the fully wound spool.
23. In a ribbon feed mechanism the combination of a shaft having a notch therein intermediate the ends thereof, said notch having a flat bottom wall, and a toothed sheet metal wheel having a central opening that conforms to the cross section of the shaft at the notched portion thereof and which wheel is flattened from a cup form to secure the wheel to the shaft at the notched portion thereof.
